CLAIM

The ornamental design for a combined golf tee and ball mark repair tool, as shown and described.

DESCRIPTION

FIG. 1 is a front elevational view thereof, this view and the opposite rear elevational view being mirror images;

FIG. 2 is a right side elevational view thereof, this view and the opposite left side elevational view being mirror images;

FIG. 3 is a perspective view showing the front, right side and top of the combined golf tee and ball mark repair tool;

FIG. 4 is a perspective view showing the front, left side and bottom of the combined golf tee and ball mark repair tool;

FIG. 5 is an enlarged bottom view thereof;

FIG. 6 is an enlarged top view thereof;

FIG. 7 is a side elevation view thereof; and,

FIG. 8 is a cross-sectional view taken on line 8-8 of FIG. 7.

FIG. 9 is a side elevation view thereof; and,

FIG. 10 is a cross-sectional view taken on line 10-10 of FIG. 9.
